[57] CLAIM

The ornamental design for a fluid-collecting receptacle having hinged mat, as shown and described.

DESCRIPTION

FIG. 1 is a perspective view of a fluid-collecting receptacle having hinged mat, showing my new design;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a side elevational view thereof.

The broken line showing of suction cups in FIGS. 3-6 is for illustrative purposes only and forms no part of the claimed design.
